(57) **CLAIM**

I claim, the ornamental design for a magnetic fin for watercraft as shown and described.

DESCRIPTION

FIG. 1 is a front elevation view of the magnetic fin for watercraft showing the present invention;

FIG. 2 is a rear elevation view thereof;

FIG. 3 is a top, front, left side perspective view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left side perspective view thereof, shown in a condition of use.

The broken lines in FIG. 7 depict portions of the magnetic fin for watercraft, which form no part of the claimed design. The broken lines in FIG. 8 show environmental structure, which forms no part of the claimed design.
